United States Patent Office

Des. 180,236
Patented May 7, 1957

180,236

BELT

Herbert R. Lewis, Oak Park, Ill., assignor of one-half to Dean Hole, Deerfield, Ill.

Application August 9, 1955, Serial No. 37,390

Term of patent 3½ years

(Cl. D3—10)

Fig. 1 is a perspective view of a belt showing my new design;

Fig. 2 is an enlarged fragmentary side elevational view of a section thereof; and

Fig. 3 is a top plan view of a portion of the enlarged fragmentary section shown in Fig. 2.

I claim:

The ornamental design for a belt, substantially as shown.
